FIG. 4.

FIG. 5.

INVENTOR

Susana A. Scheck

BY

Carlos P. Griffin

ATTORNEY.

UNITED STATES PATENT OFFICE.

SUSANA A. SCHECK, OF SAN FRANCISCO, CALIFORNIA.

GARTER.

Application filed May 2, 1922. Serial No. 557,884.

To all whom it may concern:

Be it known that I, SUSANA A. SCHECK, a citizen of the United States, residing at San Francisco, in the county of San Francisco, State of California, have invented a new and useful Garter, of which the following is a specification in such full and clear terms as will enable those skilled in the art to construct and use the same.

This invention relates to a garter and its object is to provide means whereby the garter elastic may be secured at both ends around the leg, or arm when used as a sleeve holder without sewing the ends of the elastic to the connecting device.

Another object of the invention is to provide adjustable means for connecting the garter to the stocking, or for connecting it to other clothing as may be desired, the connecting means being movable along the garter elastic to any desired position.

Another object of the invention is to provide means for connecting the ends of the elastic together which will permit the elastic to be drawn up as tight as may be desired, or loosened at will.

Other objects of the invention will appear as the description proceeds.

An embodiment of the invention is shown in the accompanying drawings in which the same reference numeral is applied to the same portion throughout, but I am aware that there may be modifications thereof.

Fig. 1 is a perspective view of the garter as it appears ready for use.

Fig. 2 is a front elevation of the plate for connecting the ends of the elastic together.

Fig. 3 is an edge view of the plate shown in Figure 2.

Fig. 4 is a front elevation of one form of the plate for connecting the clothing to the garter elastic.

Fig. 5 is an edge view of the connector shown in Figure 4, and

Fig. 6 is a side view of a modified form of connector in which the plate as an ordinary type of hose supporter is connected thereto.

The garter consists of an elastic band 1 cut of any desired length. This band usually has its ends stitched to avoid fraying, but that is not a necessity.

The ends of the garter are connected together by means of a flat plate 2. The flat

plate 2 has two triangular openings 3 and 4 formed therein, said openings being symmetrically placed at opposite ends of the plate, and adjacent the bases of the triangular openings the plate has two slots cut 60 which form four hooks 5 to 8 inclusive.

The triangular openings 3 and 4 are of such size as to enable the garter elastic to be slipped therethrough very easily, after which one edge of the garter elastic is 65 slipped under one of the adjacent hooks and then the other edge is slipped under the other adjacent hook.

When surrounding the leg or arm and with the plate pulled tightly against the 70 same by the garter elastic 1, there is no tendency for the ends of the tape to release.

In order to connect the clothing, stocking or sleeve to the elastic, plates 9 are used. These plates have two parallel slots 10 and 75 11 formed therein. In one form these plates have hooks 12 and 13 at their lower end, which hooks are connected to a safety pin 14. Any number of the fasteners may be 80 used on the garter band as may be desired, the plate being placed in position thereon by passing the garter band 1 through both of the slots 10 and 11.

If it is not desired to use the safety pins 14, the ordinary form of stocking fastener 85 having the slotted plate 15 and button plate 16 may be used. In this event the fastener is secured to a flat plate 17 with a horizontally extending slot 18 at its lower edge and having the same parallel slots 19 and 20 as 90 are used with the plate 9.

In operation the ends of the tape 1 are placed through the triangular slots 3 and 4 of the plate 2 and the short end is then bent back and hooked under the two hooks 5 and 95 6 adjacent, or 7 and 8 adjacent the opposite end, any desired adjustment of the band being easily attained.

The fastening plates 9 or 17 may be used in any desired number.

What I claim is as follows, but various modifications may be made in the construction shown in the drawings and above particularly described form, within the purview of my invention:

1. A garter fastener comprising a plate having two openings therein and having two oppositely placed prongs at each end whereby the ends of a garter tape may be passed through the two openings and then 110

under the prongs to secure the garter in a desired adjustment.

2. A garter fastener comprising a plate having two triangular openings therein with the bases of the triangles oppositely placed, said plate also having two oppositely placed prongs at each end of the plate

whereby the ends of a garter tape may be passed through said holes and may be retained in a given adjustment by being placed under said prongs.

In testimony whereof I have hereunto set my hand this 24th day of April A. D. 1922.

SUSANA A. SCHECK.
